(57) **CLAIM**

The ornamental design for an optic fitting set, as shown and described.

DESCRIPTION

FIG. 1 is an exploded perspective view of an optic fitting set; FIG. 2 is an assembled perspective view of the optic fitting set; of FIG. 1;

FIG. 3 is a perspective view of a receiving element for the optic fitting set; of FIG. 1;

FIG. 4 is a top view of the receiving element of the optic fitting set; of FIG. 3;

FIG. 5 is a forward side elevational view of the receiving element of the optic fitting set; of FIG. 3;

FIG. 6 is a rear side elevational view of the receiving element of the optic fitting set; of FIG. 3;

FIG. 7 is a bottom view of the receiving element of the optic fitting set; of FIG. 3;

FIG. 8 is a top view of an insertion member of the optic fitting set; of FIG. 1;

FIG. 9 is a bottom view of the insertion member of the optic fitting set; of FIG. 8;

FIG. 10 is a forward side elevational view of the optic fitting set; of FIG. 8; and,

FIG. 11 is a rear side elevational view of the optic fitting set; of FIG. 8.

Any broken lines depict portions of an optic fitting set that form no part of the claimed design.

1 Claim, 7 Drawing Sheets
